[57] CLAIM

The ornamental design for a no diving sign, as shown
and described.

DESCRIPTION

The FIGURE is a front elevational view of a no diving
sign showing my new design, the sign having no sub-
stantial thickness.

Dedication

Des. 287,031.—*Robert J. Cunitz*, Rockville, Md. NO DIVING SIGN. Patent dated Dec. 2, 1986. Dedication filed Apr. 20, 1987, by the *inventor*.

Hereby dedicates to the Public the entire term of said patent.
